(57) **CLAIM**

The ornamental design for an combined earring box with hinged sections, as shown and described.

DESCRIPTION

FIG. 1 is a left side elevation view of an combined earring box with hinged sections, showing our new design; FIG. 2 is a front elevation view thereof; FIG. 3 is a rear elevation view thereof; FIG. 4 is a left side elevation view thereof; FIG. 5 is a right-side elevation view thereof; FIG. 6 is a top plan view thereof; FIG. 7 is a bottom plan view thereof; FIG. 8 is a left side elevation view, shown in an open position; and, FIG. 9 is an exploded left side elevation view thereof. The broken lines showing of the earrings is in the drawings is for illustrative purposes only and forms no part of the claimed design. The broken line showing of the knobs and legs in the drawings are unclaimed subject matter.

1 Claim, 6 Drawing Sheets
